UNITED STATES PATENT OFFICE.

CALVIN O. DERFLINGER, OF RIVERTON, VIRGINIA, ASSIGNOR OF ONE-HALF TO JOHN W. MORGAN, OF RIVERTON, VIRGINIA.

CAR-COUPING.

1,102,648.

Specification of Letters Patent.

Patented July 7, 1914.

Application filed July 1, 1913. Serial No. 776,763.

To all whom it may concern:

Be it known that I, CALVIN O. DERFLINGER, a citizen of the United States, residing at Riverton, in the county of Warren and State of Virginia, have invented certain new and useful Improvements in Car-Couplers, of which the following is a specification.

This invention relates to improvements in car couplings, and has for its primary object the provision of a coupler which will be to the greatest possible extent automatic in its operation, thereby to eliminate those dangers of personal injury always inherent in any necessity requiring manual manipulation of coupling members between adjoining cars.

A further object of the invention is to provide a coupler of what is generally known as the "Janney" type, the said coupler comprising a draw bar having a head provided with an opening together with a knuckle pivotally mounted in the opening. A retaining means is carried by the head for engagement with the tail of the knuckle to restrain the same against pivotal movement and a companion or complementary knuckle is pivotally and movably mounted in the head and is adapted to coöperate with the first mentioned knuckle to engage similar parts upon another draw-head carried by an adjacent car or vehicle. A plunger is slidably mounted in the draw bar, and is engageable with the said complementary knuckle for the purpose of normally holding the same in open or receiving position.

The complementary knuckle is provided with fingers which engage the primary or first mentioned knuckle and is adapted to swing the same to an open position when released from said retaining means. The said complementary knuckle is mounted for bodily movement in the arc of a circle. The advantage gained by this arrangement is that the parts may have maximum movement and at the same time they do not project or extend to any material degree beyond the side edges of the head of the draw bar. At the same time the coupler is provided with sufficient flexibility to enable members of two couplers to readily engage each other and to permit the members to swing or work freely as the cars are passing around curves or at other times.

With these and other objects in view, the invention consists in certain novel features

of construction as hereinafter shown and described, and then particularly pointed out in the claim and in the drawings, illustrative of the preferred embodiment of the invention.

In the accompanying drawings:—Figure 1 is a top plan view of the coupler. Fig. 2 is a side elevation of the same. Fig. 3 is a horizontal sectional view of the coupler taken on the lines 3—3 of Fig. 5. Fig. 4 is a horizontal sectional view of the coupler taken approximately at the axis of the same showing the parts in an open position. Fig. 5 is a longitudinal sectional view of the coupler taken on the line 5—5 of Fig. 3. Fig. 6 is a similar view taken on the line 6—6 of Fig. 3. Fig. 7 is a transverse sectional view, taken on the line 7—7 of Fig. 3. Fig. 8 is a perspective view of the complementary knuckle. Fig. 9 is a perspective view of the means for retaining the primary knuckle against pivotal movement. Fig. 10 is a perspective view of the primary knuckle of the coupler.

Corresponding and like parts are referred to in the following description and indicated in all the views of the accompanying drawings by the same reference characters.

The coupler comprises a draw bar 1 having at one end an enlarged head 2 provided at its end with a recess 3. The said recess 3 is disposed generally across the end of the head 2 in the usual manner, but it is provided with a rear wall 4 which is disposed at an acute angle to the axis or long dimension of the drawbar 1. The head 1 is provided at the rear portion of the recess 3 with a curved compartment 5, the lower end of which enters the rear portion of the said recess. In this compartment 5 is slidably or movably mounted a curved retaining member 6. This member 6 is provided at one side with a shoulder 7, beyond which the member is continued into an extremity 8, which is adapted at times to extend well into the recess 3. A pin 9 is slidably mounted in the upper portion of the head 2 and is pivotally connected at its lower end with the upper inner end of the member 6. Therefore when the pin 9 is lifted or moved longitudinally in a vertical direction the member 6 is raised whereby its extremity 8 is withdrawn from the recess 3 or substantially so.

A knuckle 10 is pivotally mounted in the

head 2 and is provided with a tail 11 which is normally received in the recess 3. The knuckle 11 is provided between its point of pivotal connection with the head 2 and the inner end of the tail 3, with shoulders 12 which in turn are provided with gaps 13. When the member 6 is in its lowermost position its extremity 8 is located in the path of movement of the inner end of the tail 11 of the knuckle, and the forward end of the extremity 8 is beveled as at 14, so that when the inner end of the tail 11 engages the said extremity as the knuckle is moved to a closed position, the member 6 is forced in an upward and rearward direction whereby the end of the tail of the knuckle may pass between the side of the extremity 8 and the side wall of the recess 3. Therefore, when the knuckle is closed it is secured or held in a closed position. When the knuckle is secured in a closed position as above stated, the shoulder 6 may encounter the end of the tail 11 whereby downward movement of the member 6 is checked. When the member 6 is raised, as above described, the tail 11 of the knuckle is released and the knuckle 10 is free to swing in a forward direction. The head 2 is provided at its top and bottom side with arcuate slots 15, the inner ends of which enter the recess 3. A complementary knuckle 16 is located in the recess 3 and carries a pin 17, the end portions of which are slidably received in the arcuate slots 15. The complementary knuckle 16 is provided with spaced fingers 18 which straddle the tail 11 of the knuckle 10 and the said fingers are provided with forwardly disposed extremities 19 which are adapted to enter the gaps 13 in the shoulders 12. The forward edges of the fingers 18 at all times bear against the edges of the shoulders 12. The complementary knuckle 16 is provided at its inner or rear side with a socket 20 which receives the forward rounded end of a plunger 21. This plunger 21 is mounted in a passage 22 provided in the draw bar 1 and a coil spring 23 is interposed between the inner end of the plunger 21 and the end of the passage 22. The spring 23 is under tension with a tendency to hold the outer or rounded end of the plunger 21 in the socket 20 of the complementary knuckle 16.

When the knuckle 10 and the complementary knuckle 16 are in their open positions the parts are positioned as shown in Fig. 4 of the drawings, when the ends of both knuckles are extended beyond the end of the head 2. The plunger 21 and the spring 23 hold the inner portion of the complementary knuckle 16 toward the pivot of the knuckle 10 and the engagement of the fingers 18 and their extremities 19 with the shoulders 12 and gaps 13 hold the tail 11 of the knuckle 10 approximately at the mouth of the recess 3. Thus these parts are in posi-

tion to receive or engage similar parts of another coupler. As the said parts of another coupler move between the knuckles 10 and 16 the inner ends of the said knuckles are swung in an inward direction and the plunger 21 is pushed in against the spring 23. The inner ends of the knuckle 10 and 16 move in an inward direction until the parts assume the positions shown in Fig. 3, when the member 6 and its extremities 8 engage or move across the path of movement of the tail 11 of the knuckle 10 and hold the parts in closed position. Thus the knuckles of one coupler are engaged with the knuckles of another coupler. 80

Presuming that the parts are in position as shown in Fig. 3, it is possible for the knuckle 10 of another coupler to interlock with the knuckle 10 of the coupler as shown in said figure while in closed position for the reason that the knuckle 10 of the approaching coupler may strike the complementary knuckle 16 and move the same bodily in the recess 3 along the arcuate slots 15, so that the knuckle 10 of the approaching coupler will enter between the knuckles 10 and 16 of the coupler shown and thus the couplers of two cars may be interlocked with each other irrespective of the condition or position of the knuckles of either or both couplers. The head 2 is provided at the side wall of the recess 3 with a thickness of material 24 which is located in the path of movement of the tail 11 of the knuckle 10. This thickness of material serves as a buffer in case the tail 11 should strike the same and consequently it will prevent damage being done to the parts due to the impact of the couplers being brought together forcibly. Therefore it will be seen that a coupler of simple structure is provided and that its parts are of substantial form and configuration and the members of one coupler will positively engage the members of another coupler, and at the same time there will be ample flexibility to permit the couplers to have desired lateral relative movement. Furthermore the coupler will automatically operate to interlock with each other irrespective of the positions of their knuckle without requiring the necessity of an operator going between the cars, and the pivoted knuckle of one coupler may be readily released to permit the cars to be uncoupled. 115

Having described the invention what is claimed, is:—

A car coupler, comprising a head provided with a recess and longitudinally extending slots, a knuckle pivotally mounted within one side of the recess and provided with a laterally extending tail and shoulders arranged upon opposite sides of the tail adjacent the base thereof, locking means to detachably engage the tail, a complementary knuckle provided with spaced laterally ex- 130

tending fingers receiving the tail therebetween and having extremities engaging said shoulders, a pin passing transversely through the complementary knuckle and mounted in 5 the slots to turn therein and move longitudinally thereof, a plunger longitudinally movably mounted in the head with its free end slidably engaging the complementary knuckle inwardly of the pivot thereof, and

resilient means engaging the plunger to move it outwardly toward the complementary knuckle.

In testimony whereof I affix my signature in presence of two witnesses.

CALVIN O. DERFLINGER.
